United States Patent Office

Des. 199,997
Patented Jan. 5, 1965

199,997

YARN CLEARER

Siegfried Peyer, Kantonstrasse, Bach, Zurich, Switzerland

Filed July 22, 1963, Ser. No. 75,907

Term of patent 14 years

(Cl. D47—5)

FIG. 1

I claim:

The ornamental design for a yarn clearer, as shown.
